DESIGN FOR A DISPLAY CASE

John B. Guttman, Elmhurst, N. Y., assignor to Arrow Manufacturing Company, Incorporated,
Hoboken, N. J., a corporation of New Jersey

Application May 7, 1941, Serial No. 100,824

Term of patent 7 years

to all whom it may concern:

Be it known that I, John B. Guttman, a citizen of the United States, residing in Elmhurst, County of Queens, and State of New York, have invented a new, original, and ornamental Design for a Display Case, of which the following is specification, reference being had to the accompanying drawing, forming part thereof. Figure 1 is a perspective view of a display case, showing my new design;

The dominant features of the design are shown in full lines.

I claim:

The ornamental design for a display case, substantially as shown and described.

JOHN B. GUTTMAN.
